FOLDING BOX

Marshall I. Williamson, Edgewater, N. J.

Application January 18, 1934, Serial No. 707,165

13 Claims. (Cl. 229—16)

This invention relates to folding boxes and the method of making the same.

My invention, as to an aspect thereof, relates to a collapsible folding-box-blank having a body of generally rectangular contour, suitably scored and/or creased, which when set-up presents side walls of non-rectangular configuration.

My invention, as to an aspect thereof, relates to a collapsible folding-box-blank having a body of generally rectangular configuration, suitably scored and/or creased, which when set-up presents side-walls symmetrically related to one another and disposed out of normal relation with the bottom and top of the resulting box.

My invention, as to an aspect thereof, relates to a collapsible folding-box-blank, suitably scored and/or creased in the body of the blank or provision for the side-walls, the bottom and its associated end-flaps being connected to the body of the blank as extensions, and also the top and its associated end-flaps, whereby upon folding the blank and setting-up the box, portions of the body of the blank, disposed in serial relation to one another from top to bottom, are flexed out of uni-planar relation.

Preferably, such blanks are of integral material. The procedure for forming the blank into collapsed sleeve-like form is conveniently had by securing of the side-edges of the blank to one another, as by gluing, stapling, taping, stitching or by other suitable means or procedure.

The embodiments of my invention having body-portions of generally rectangular configuration possess the advantage of affording manufacture thereof on present-day standard automatic machines, involving the application of glue or other adhesive upon the blank adjacent one edge of the body of the blank and also the folding of opposing edge-portions of the body of the blank upon one another, accompanied by application of pressure for the securing of the blank into collapsed sleeve-like form.

Numerous types of embodiments of my invention result in boxes having variously contoured sub-faces, i. e., facets, the same being disposed in symmetrical relation to one another. Such facets may be formed in the side-walls or may be formed in the end-walls, i. e., top and bottom, or in both side-walls and end-walls and at the corners of the box.

In general, boxes formed pursuant to my invention, produced either on standard automatic folding-box-making machines or by manual operation, embody blanks, each of which comprises

a body, suitably scored and/or creased, for provision of the side walls, and further scored and/or creased with fold lines non-parallel to said side defining score and/or creased lines, and further comprises extensions connected to the body of the blank for the end-walls, and upon setting-up the box, that is, by securing of edge-portions of the body of the blank and displacement of the portions of the blank-body relative to one another, the edges of adjacently related side-walls are disposed out of coincidence with the corners of regulation types of boxes.

Further features and objects of the invention will be more fully understood from the following detail description and the accompanying drawings, in which—

Fig. 1 is a perspective view of an embodiment of my invention having reentrantly angular, dual-planed side-walls; Fig. 2 is a plan view of the inner face of the scored or creased blank of the same; and Fig. 3 is a plan view of the blank partly folded upon itself preparatory to securing its opposing side-edges to one another by means of adhesive.

Fig. 4 is a perspective view of an embodiment generally similar to Fig. 1, but having curved in lieu of angular side-wall-edges and arcuate in lieu of dual-planed-side walls.

Fig. 5 is a perspective view of a further embodiment of my invention having non-rectangular, single-planed side-walls; and Fig. 6 is a plan view of the outer face of the scored or creased folding blank of the same.

Fig. 7 is a perspective view of an embodiment of my invention, illustrating another form of non-rectangular side-walls and a fractional rotation of the top and bottom; and Fig. 8 is an outer plan view of its scored or creased folding blank.

Fig. 9 is a perspective view of one form of my invention, having faceted side-walls and giving rise to top and bottom of dissimilar contour; and Fig. 10 is a plan view of the outer face of its scored or creased folding blank.

Fig. 11 is a perspective view of an embodiment of my invention, illustrating a type of re-entrant corner-facets interposed between dual-planed side-walls; Fig. 12 is a horizontal cross section on line 12—12 of Fig. 11, on a somewhat enlarged scale; Fig. 13 is a detail sectional view on line 13—13 of Fig. 12; Fig. 14 is a plan of the inner face of the scored or creased blank in flat status of the embodiment shown in Figs. 11, 12, and 13, on a reduced scale; and Fig. 15

is a plan view of the blank of Fig. 14, indicating the area of application of adhesive and showing the blank partly folded upon itself, preparatory to securing its opposing side-edges to one another.

Fig. 16 is a perspective view, partly broken away, showing another embodiment of my invention having curved corner-facets between arcuate side-walls; and Fig. 17 is a detail horizontal section on line 17—17 of Fig. 16.

Fig. 18 is a perspective view of another embodiment of my invention having re-entrantly curved corner-facets between dually-arcuate side-walls; and Fig. 19 is an outer plan view 15 of its blank, showing also the area of application of adhesive.

Fig. 20 is a perspective view of a further embodiment of my invention; and Fig. 21 is a plan view of the outer face of its blank, indicating 20 also the area of application of the adhesive.

Fig. 22 is a perspective view of an embodiment of my invention illustrating both side and end-wall facetting; and Fig. 23 is a plan view of the 25 outer face of the scored or creased folding blank of the same.

Fig. 24 is a perspective view of an embodiment of the type of Fig. 22, illustrating another form of side and end-wall facetting; and Fig. 25 is an outer plan view of its scored or creased 30 folding blank.

Fig. 26 is a perspective view of another facet-walled embodiment of my invention, showing in particular the partly coincidental locating of the two primary fold-lines of the blank with two of 35 the score or crease-lines defining edges of the corner-facets of the box. The embodiment shown in Fig. 25 also illustrates a form of tri-planar side-walls.

Fig. 26 is a perspective view of another embodiment.

Referring to Figs. 1, 2, 3, and 4, of the drawings, the embodiment 32 shown in Fig. 1 and the embodiment 33 shown in Fig. 4 present boxes having non-rectangular side-walls, formed from single-piece blanks, suitably scored or creased, and arranged to be folded over flatwise, at locations determined by two primary score or crease-lines disposed parallel to each other and to the side-edges of the blank, to afford 45 securing of the opposing side-edges of the blank by adhesive, under pressure, or other suitable means.

The blank from which the embodiment 32 is formed, is substantially rectangular in its body 55 portion, (see Fig. 2,) being, at its right-hand side-edge 32a, substantially rectilinear, and likewise at its upper aligned end-edges 32b, 32c, its left-hand side-edge 32d and its lower end-edge 32e. As shown, the blank further comprises 60 the upwardly extending end-portion 32f scored or creased to fold at 32g to serve as the upper or top end-closure; its tongue or tuck-portion 32h is shown integral with the top 32f at the score or crease-line 32j.

The lower or bottom end-closure and its tuck 65 may be, and in this instance, are of like blanked portions, extending from the lower edge of the body of the blank, related similar to the top and its tuck, and bearing like reference characters 70 supplemented with a prime.

The smaller end-portions to the left of the top-portion 32f are shown at 32k and 32m, respectively integrally connected with the body of the blank at the score or crease-lines 32n and 32p; these end-portions serve as retaining-flaps

in association with the top to maintain the box square and rigid when set-up. Between the right-hand edge of the end-flap 32k and the top 32f is a line 32q of severing. The end-portions 32k' and 32m', serving as retaining-flaps in association with the bottom 32f', and their respective score or crease-lines 32n' and 32p' are related to the remaining portions of the blank similar to the end-flaps of the top, excepting that there are the two lines of severing 32q' 10 and 32q'' respectively, to separate the end-flaps 32k' and 32m' from the bottom 32f'. 5

The particular non-rectangular and dual-planed formation of the side-walls, see Fig. 1, is attained by scoring or creasing the body of 15 the blank at the indicated side-wall edge-lines, that is, the re-entrantly angled lines 32r, 32s, 32t, 32u and by the shape of the left-hand side-edge-line 32d. Coacting with such non-rectilinear score or crease-lines is a transverse score 20 or crease-line 32v, which, in this instance, is rectilinear and extends from the right-hand side-edge-line 32a to the left-hand side-edge-line 32d of the blank.

The stated re-entrantly angled lines 32r to 25 32u, extending generally perpendicularly, and the coacting transverse score or crease-line 32v are premised upon the derivation of a box having substantially symmetrical non-rectangular dual-planed side-walls, the opposite faces of which 30 conform to but are reversely contoured relative to one another.

Upon blanking-out, scoring or creasing the blank 32 as above indicated, and by further scoring and/or creasing the blank with primary fold lines 32x and 32z, referred to more particularly hereinafter, and upon application of glue or other adhesive, as over the area 32w, which is upon the under or outer face of the blank as it appears in Fig. 2, the blank is folded upon itself, i. e., firstly, 40 by upward movement of its right-hand side-portion at the primary fold-line 32x to its position as is indicated in Fig. 3. In the position as viewed in Fig. 3 the area 32w of application of the adhesive is uppermost and therefore visible. 45

The securement of the thus folded blank is completed by folding, secondly, the opposing side-portion 32y on the other primary fold-line 32z, pressure being applied to complete the bonding of the adhesive, thus giving rise to the sleeve-like 50 form of the box, when in collapsed status. It is observed that the two mutually spaced rectilinear fold lines 32x, 32z, are parallel to the rectilinear side edge 32a of the lateral and glue-area extension 32w, at one side of the blank, and that the 55 extreme edge portions of the side opposite said rectilinear side edge 32a are substantially parallel to said rectilinear side edge 32a, and accordingly upon folding the blank along said rectilinear fold lines 32x, 32z, portions of the blank adjacent said 60 extreme side edge portions are brought into overlying relation with said lateral glue-area extension, thus enabling the blank to be folded on standard box-making machinery into a collapsed sleeve-like glued blank. 65

Upon grasping the thus doubly folded, collapsed, sleeve-like glued blank, and applying pressure inwardly at the oppositely disposed primary fold-lines 32x and 32z, the box is expanded out of its original flat-folded collapsed status, the respective side-walls being displaced relatively to one another and flexed into their respective non-rectangular dual-planed formation. The final 70 positioning of the side-wall-areas, and therewith the top and bottom, is effected by bending over 75

the respective end-flaps 32k, 32m at the top, the end-flaps 32k' and 32m' at the bottom, and thereafter bending the top 32f and likewise the bottom 32f' and inserting their respective tuck-flaps 32h and 32h', whereupon the final set-up box illustrat- 5 ed in Fig. 1 is attained.

It will be observed that, in the original flat-folding of the blank on the above stated two primary fold-lines 32x and 32z, the side-edge-line 10 32a of the first-folded right hand side portion of the blank is located parallel to and slightly within or to the right of the second primary fold-line 32z (see Fig. 3) so as to permit the free folding of the left-hand side-portion 32y thereupon. It will 15 also be noted that, by such original flat-folding of the blank, the re-entrantly angled left-hand side-edge-line 32d is brought coincidental with the corresponding re-entrantly angled side-wall edge-line 32r.

Assuming the blank, as shown in Fig. 2, to be 20 formed to original flat-folded sleeve-like status on a standard automatic folding-box-making machine involving the usual glue-wheel, the area of application of the glue is indicated at 32w, (see 25 Fig. 3) and the corresponding area of bonding of the left-hand side-portion of the blank, when folded thereupon, is indicated at 32w'. The natural coincidental extent of the said bonding area 32w' and of the said glue application area 32w 30 accordingly gives rise to two triangular unglued areas 32w'' and 32w'''.

Upon setting-up the box, these stated unglued areas are held flush with the underlying corresponding glueless areas of the right-hand side- 35 edge-portion of the blank, and their cut edges held coincidental with the re-entrantly angled side-wall edge-line 32r, by the inward folding of the end-flaps 32m and 32m'.

It will be observed that the resulting seam-line 40 is thus made not coincident with the primary fold-line 32z and it is also noted that in this type of embodiment of my invention, each primary fold-line 32x and 32z is positioned intermediate—and in the instance shown in Fig. 1, sub- 45 stantially midway—between the side-wall edge-lines 32s, 32t and between the blank's side-edge-line 32d and the side-wall edge-line 32u.

The embodiment 33 shown in Fig. 4 corresponds generally to that shown in Fig. 1, and like parts 50 are designated by like reference characters, that is to say, the reference number 33 supplemented by corresponding letters and primes. However, the score or crease-lines, 33s, 33t and 33u, Fig. 4, and likewise the hidden score or crease-line 33r, 55 are curved in lieu of being re-entrantly angular and the side-walls arcuate instead of dual-planed.

The box 34 as shown in Fig. 5, is formed from the blank shown in Fig. 6, the corresponding parts of the blank shown in Fig. 6 as compared with 60 the blank shown in Fig. 2 bearing the reference number 34 supplemented by corresponding reference letters and primes. It will be observed, as appears in Fig. 5, that the side-wall edges in this form of my invention extend rectilinearly from 65 top to bottom and are oriented to a position disposed outside of the planes of contiguous side-walls of a regulation rectangular box, and as illustrated in Fig. 5, the extent of orientation, indicated by the direction of extension of the top 70 relative to the bottom, is approximately ninety degrees.

The box 35 as shown in Fig. 7 is formed from the blank shown in Fig. 8 and portions of its blank corresponding to comparable portions of the 75 blank of Fig. 2 are designated by the reference

number 35 supplemented by corresponding letters and primes. In the embodiment shown in Fig. 7, the side-walls are curvedly triangular in shape and compoundly arcuate of surface and extend correlatively from the top and the bottom, respectively, of the box. Also its top is rotated through an approximate angle of forty-five degrees relative to its bottom. 5

The embodiment 36 shown in Fig. 9 is formed from the blank shown in Fig. 10 and parts of its 10 blank comparable to parts of the blank shown in Fig. 2 are designated by the reference number 36 supplemented by corresponding reference letters and primes. The box as illustrated in Fig. 9 gives rise to a bottom of rectangular formation 15 and a top of hexagonal formation.

The box 37 shown in Fig. 11 is formed from the blank shown in Fig. 14 and parts of its blank comparable to parts of the blank shown in Fig. 2 20 are designated by the reference number 37 supplemented by corresponding reference letters and primes.

The box illustrated in Fig. 11 has a rectangular top and bottom and dual-planed re-entrantly angular side-walls similar to those of the box 25 shown in Fig. 1 but with correlatively faceted corner areas interposed between the respective side-wall areas. Such re-entrantly faceted corner areas arise from the introduction of additional re-entrantly angled side-wall-defining 30 score or crease-lines 37rr, 37ss, 37tt and 37uu, so disposed that their upper and lower ends meet, respectively, the upper and lower ends of the original side-wall-edge-defining score or crease- 35 lines 37r to 37u.

A further feature of the box shown in Fig. 11 is that of the tabs 37aa, 37a'a' (see Fig. 14) appended to the left-hand side-edges of the top and bottom end-flaps 37m, 37m', respectively. These tabs serve to supplement the inward folding of the said top and bottom end-flaps in their incidental function of thus bringing and maintaining the unglued areas 37w'', 37w''' of the left-hand side-edge-portion of the blank flush with the underlying corresponding glueless areas of 45 the right-hand side-edge-portion of the blank, as described for the box shown in Fig. 1. Thus, upon folding inwardly the end-flaps 37m, 37m', each of the said tabs 37aa, 37a'a', being first also folded inwardly, forms an acute angle with its 50 respective end of the free, i. e. unglued, left-hand side-edge-line 37d of the blank, so that when fully inserted, as shown in Fig. 11, the top and bottom end-edge-lines 37b, 37b' of the right-hand side-portion of the blank are locked securely 55 in the respective apexes of the aforesaid acutely formed angles.

The final tucked-in position of the respective bottom end-closure portions of the box, thus attained, is shown in Fig. 12, viewed downwardly on 60 the section 12—12 indicated in Fig. 11; a detail cross-sectional view on the line 13—13 of Fig. 12 is shown in Fig. 13, further illustrating in particular the final positioning of the lower end-flap-tab 37a'a'.

The box shown in Figs. 16 and 17 conforms largely to the box shown in Fig. 11, and like portions are designated by the reference number 38 65 supplemented by corresponding reference letters and primes. In the box shown in Fig. 16, the edges of the corner-facets and the side-walls extend curvedly from the top to the bottom, whereas as the box shown in Fig. 11 has re-entrantly angular facet and side-wall edges which extend 70 from the top to the bottom.

At the partly broken away corner of the box shown in Fig. 16 and also in Fig. 17 is illustrated a slight flexing of the corners of the tuck-portion 38h of the top end-closure 38f to permit the tuck, 5 upon being inserted, to conform more nearly to the contour of the box at such location. The stated flexing of the said tuck-corners also results in the side-edges of the tuck forming an acute angle instead of a right angle with the side-edge 10 of the top end-closure, having thus the effect of more securely locking the tuck in position than would otherwise be the case.

The box 39 shown in Fig. 18, formed from the blank shown in Fig. 19, is of the general type of 15 the box shown in Fig. 11 and like parts are designated by the reference number 39 supplemented by corresponding reference letters and primes. The facet-edges of this box, however, and the coincidental edges of its side-walls, as appears in 20 Fig. 18, are re-entrantly curved instead of angular, and it will be noted, also, that the oppositely re-entrant curvatures of the stated facet and side-wall edges induce reversely corresponding 25 arcuate surfaces of the respective facet and side-wall areas when they are flexed into being as the box is set up, similarly as described with respect to the box shown in Fig. 1.

Fig. 19 further indicates at 39w the application 30 of the adhesive, either manually or by "printing" or other procedure, to the whole of the area to the left of the side-wall edge-line 39r at the left-hand side portion of the body of the blank, which is here shown outer face up. (This has heretofore been referred to as the right-hand side of 35 the blank where shown inner face up as in Figs. 2 and 14.) Thus, upon doubly folding the blank upon itself at the primary fold-lines 39x, 39z, a fully glued overlap and seam is provided in lieu of the partly unglued overlap and resulting free 40 side-edge-line, as in the case of the blanks shown in Figs. 2 and 14.

Fig. 19 still further illustrates location of the top and bottom end-closures directly in line with one another, at the same side of the blank body, to 45 form what is commonly referred to as a "straight tuck" box, whereas all other embodiments shown, except those illustrated in Figs. 7 to 10, are of the so called "reverse tuck" style.

The box 40, shown in Fig. 20, is formed from 50 the blank shown in Fig. 21. This type of my invention has a width dimension greater than its height dimension and in this sense has corner-facets at the ends of the box. The respective parts of the blank and its score or crease lines 55 are designated 40 with reference characters and primes corresponding to those designating like parts of the blank shown in Fig. 2. The box shown in Fig. 20 also illustrates a form of supplemental closure "lock", that is, a slot 40A and 60 cooperating tab 40B for the top closure 40f, see Figs. 20 and 21, and corresponding slot 40A and tab 40B for the bottom closure 40f', particularly effective in instances of boxes of considerable width.

65 The box 41, shown in Fig. 22, is formed from the blank shown in Fig. 23, the respective parts of which are designated 41 with reference letters and primes corresponding to those designating like parts of Fig. 2. In the main, the body of the 70 blank here shown corresponds generally to that of the blank shown in Fig. 6, but in this instance, faceted areas, created by the sets of score or crease lines 41n, 41nn and 41p, 41pp, are located at the upper ends of two opposite sides of the 75 resulting box, giving them each an inwardly

sloping gable-end formation. The top end-closure, in this embodiment, consequently has re-entrantly angled side-edges and a laterally extending crease-line 41gg whereon the same is folded to enable it to conform to the said gable-end formation of the sides. The top of the illustrated box is thus of dual-planed surface when closed. 5

The box 42, shown in Fig. 24, is formed from the blank shown in Fig. 25, and corresponding parts of the blank and resulting box are designated 42 with reference characters and primes corresponding to those of Fig. 23, and, in turn, to those of Fig. 2. The box here illustrated has both faceted top and faceted front and back 15 walls, the whole being otherwise generally similar to the box shown in Fig. 22.

The box 43 shown in Fig. 26 illustrates particularly, as has been stated, the partly coincidental locating of certain of the corner-facet edge-lines with the two primary fold-lines of the blank. In the particular embodiment illustrated, the box has both top and bottom of rectangular shape but a main body portion of hexagonal cross-section, which latter is occasioned by eliminating 25 one of the normally two pairs of oppositely disposed side-walls and enlarging the corner-facets to an extent that their respective side-edge-lines, 43ss, 43t, and 43r, 43uu, which previously adjoined the said eliminated side-walls, are brought 30 coincidentally with each other and with major portions of the respective primary fold-lines 43x, and 43z (not visible in Fig. 26) which formerly traversed the centers of the two eliminated side-walls. 35

It is to be noted here, also, that the corner facets in this embodiment are of hexagonal shape and that both they and the comparatively contoured remaining side-walls are of tri-planar surface. And it is further to be observed that, 40 in the event of non-elimination of the said form of oppositely disposed side-walls, the primary fold-lines 43x, 43z might still extend in part coincidentally with side-edge-lines of two oppositely disposed corner-facets, though such primary fold-lines would thus no longer traverse centrally the respective end-flaps of the box.

As appears from the foregoing, my invention, as to certain types thereof, is directed to boxes formed from integral blanks, of suitable foldable 50 material, each having a main body portion with suitably contoured and thereto appended end portions, to serve as closures of the box when formed, the said blanks being appropriately scored or creased to effect, when formed and 55 set up, a collapsible folding-box having side and/or end walls of nonrectangular and/or non-uni-planar formation.

However, boxes of such unusual configuration, produced pursuant to my invention, need not of 60 necessity be formed from wholly integral blanks, but may, if desired, be formed of several pieces of material and either wholly or in part of other than strictly foldable material.

Paper or paper-board (box-board) is a highly 65 suitable and in most respects preferable material from which boxes pursuant to my invention may be produced, but other materials in either sheet or web form, such as various forms of fibre-board, fabric, thin metals, cellulose compositions, phenol-resinous and/or other composition materials and substances may also be employed.

The more advantageous types of embodiments 70 of my invention are formed from blanks, the overall area of each of which is of substantially rec- 75

tangular contour and the side edges, particularly, of which are generally parallel. Moreover, the more advantageous types of embodiments of my invention provide also for scoring or creasing of the blank in such manner as to afford two suitably located primary fold-lines both parallel to the aforesaid parallel side-edges of the blank, and therefore to each other, whereon the blank may be first truly and squarely folded, from each side, 10 upon itself to effect the necessary over-lapping and ultimate securement to each other of the two side edges of the blank to form the same to primary collapsed sleeve-like status, thus enabling, through this point in the formation of the resulting box, the maintenance of a generally true rectangular shape of the originally flat-folded, sleeve-like formed blank. These two attributes of the more advantageous types of embodiments of my invention render their blanks wholly 15 adaptable to such primary flat-folding and securement to each other of their sides upon present-day standard automatic folding-box-making machines.

Referring in this respect, to the blanks shown 20 in Figs. 6, 8 and 10 and also to the blanks shown in Figs. 23 and 25, it will be observed that the blank-portions appearing as flaps extending laterally of the respective right-hand side-edges thereof, and designated respectively 34aa, 35aa, 30 36aa, 41aa and 42aa, serve to render the respective right-hand side-edges of the blanks substantially parallel to their respective left-hand side-edges, thus imparting to the body of each blank the above stated generally true rectangular contour necessary to its proper treatment in such 35 standard automatic folding-box-making machines.

Again, however, my invention is not to be construed as limited by the above stated provisions 40 for manufacture upon such standard or any other automatic machinery, as various embodiments not so provided may be satisfactorily produced in other ways, both manually and/or by machine.

Furthermore, various of the more advantageous 45 types of embodiments of my invention are readily adapted to automatic machine filling, closing and/or sealing, though they need not of necessity be so filled, closed and/or sealed. In this respect, it is to be understood that suitable modifications, 50 either of a special or wholly conventional nature, may be made in the respective closure portions of the various embodiments of my invention so as more fully to adapt them to such automatic machine filling, closing and/or sealing, without 55 departing from the general scope of my invention.

An incidental feature to be noted with respect 60 to the end-flaps (see 32m, 32m', 32s, 32s', Fig. 2) generally incorporated in embodiments of my invention, is that of the availability and serviceability of such flaps to facilitate removal of contents of the box. When the box has been set up and packed with a pourable commodity, and later opened, the scoring or creasing of such an end flap in effecting the respective primary fold-line 65 of the blank, and the subsequent original flat-folding of the blank thereon, causes it, when opened, to assume a convenient trough-like "pouring-spout" formation and thus to facilitate materially the dispensing of the commodity.

70 Whereas I have described my invention by reference to specific forms thereof, it will be understood that many changes and modifications may be made without departing from the spirit of the invention.

75 I claim:

1. A blank for a box having a body portion providing for the side walls of the resulting box, extensions connected at the top and bottom of the blank providing for the top and its associated end flaps and the bottom and its associated end flaps respectively, the body of the blank being scored or creased non-rectilinearly from top to bottom to provide when set-up symmetrical side walls of the box related to one another at angles other than right angles and at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 10 15

2. A blank for a box having a body portion providing for the side walls of the resulting box, extensions connected at the top and bottom of the blank providing for the top and its associated end flaps and the bottom and its associated end flaps respectively, the body of the blank being scored or creased by sets of mutually serially related scored or creased lines, the lines of each set extending from top to bottom at an angle respectively to one another, to provide when set-up side walls disposed in serial relation from top to bottom in re-entrant planes, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 25 30 35 40

3. A blank for a box having a body portion providing for the side walls of the resulting box, extensions connected at the top and bottom of the blank providing for the top and its associated end flaps and the bottom and its associated end flaps respectively, the body of the blank being scored or creased by parallelly extending sets of mutually serially related scored or creased lines, the lines of each set extending at an angle respectively to one another to provide when set-up symmetrically disposed sets of side walls disposed in serial relation from top to bottom in re-entrant planes, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 50 55 60 65 70

4. A blank for a box having a body portion 75

providing for the side walls of the resulting box, extensions connected at the top and bottom of the blank providing for the top and its associated end flaps and the bottom and its associated end flaps respectively, the body of the blank being curvedly scored or creased plurally from top to bottom to provide when set-up side walls disposed in serial relation from top to bottom in curved surfaces, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension.

5. A blank for a box having a body portion providing for the side walls of the resulting box, extensions connected at the top and bottom of the blank providing for the top and its associated end flaps and the bottom and its associated end flaps respectively, the body of the blank being curvedly scored or creased plurally 25 symmetrically from top to bottom to provide when set-up symmetrically disposed sets of side walls disposed in serial relation from top to bottom in curved surfaces, and related at angles other than right angles to the top and bottom, said blank being further provided at one side with a lateral extension having a rectilinear side edge, said blank being further provided with two 30 mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension.

6. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being non-rectilinearly scored or creased plurally symmetrically from top to bottom to provide when set-up side walls of the box related to one another at angles other than right angles and at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension.

7. A blank for a box having a body portion of substantially rectangular configuration providing for the side walls of the resulting box, extensions connected at the top and bottom of the blank providing for the top and its associated end flaps

and the bottom and its associated end flaps respectively, the body of the blank being symmetrically non-rectilinearly scored or creased plurally from top to bottom to provide when set-up symmetrical side walls of the box related to one another at angles other than right angles and at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 20

8. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being plurally scored or creased by sets of mutually serially related scored or creased lines the lines of each set extending rectilinearly from top to bottom at an angle respectively to one another, to provide when set-up side walls disposed in serial relation from top to bottom in re-entrant planes, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 30

9. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being plurally scored or creased by parallelly extending sets of mutually serially related scored or creased lines the lines of each set extending rectilinearly from top to bottom at an angle respectively to one another, to provide when set-up symmetrically disposed sets of side walls disposed in serial relation from top to bottom in re-entrant planes, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 60

10. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being plurally curvedly scored or creased from top to bottom to provide when set-up side walls disposed in serial relation from top to bottom in curved surfaces, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 5
15. 11. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being plurally curvedly symmetrical from top to bottom scored or creased to provide when set-up symmetrically disposed sets of side walls disposed in serial relation from top to bottom in curved surfaces, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 10
20. 12. A blank for a box having a body portion of substantially rectangular configuration providing for the side walls of the resulting box, extensions connected at the top and bottom of the blank providing for the top and its associated end flaps and the bottom and its associated end flaps respectively, the body of the blank being plurally curvedly symmetrical from top to bottom scored or creased to provide when set-up symmetrically disposed sets of side walls disposed in serial relation from top to bottom in curved surfaces, and related at angles other than right angles to the top and bottom, said blank being further provided at one side with a lateral extension having a rectilinear side edge, said blank being further provided with two mutually spaced rectilinear fold lines extending parallel to said rectilinear side edge, the extreme sidewise edge portions of the side of said blank opposite said rectilinear edge side being parallel to said rectilinear side edge, thereby affording flat foldability of the blank upon itself along said two mutually spaced rectilinear fold lines, with portions of said opposing side of the blank overlying said side extension. 15
25. 13. A container formed of a blank of foldable material, the walls thereof when the container is set up, comprising alternate concave and convex panels, irregular score lines defining the marginal edges of said concave and convex panels and serving the connection between the panels, said irregular score lines being arranged in pairs in opposed relation whereby setting up of the box produces the aforementioned concave and convex panels and produces tension therein, said blank being further provided with two mutually spaced rectilinear fold lines extending non-parallelly to said irregular score lines, said blank further comprising a lateral extension at one 20 side of the blank having a rectilinear side edge extending parallel to said two mutually spaced rectilinear fold lines, the extreme sidewise edge portions of the side of the blank opposing said rectilinear side edge being substantially parallel to said rectilinear side edge, thereby affording flat foldability of the blank upon itself, with opposing portions of the blank overlying one another. 25
30. 14. A container formed of a blank of foldable material, the walls thereof when the container is set up, comprising alternate concave and convex panels, irregular score lines defining the marginal edges of said concave and convex panels and serving the connection between the panels, said irregular score lines being arranged in pairs in opposed relation whereby setting up of the box produces the aforementioned concave and convex panels and produces tension therein, said blank being further provided with two mutually spaced rectilinear fold lines extending non-parallelly to said irregular score lines, said blank further comprising a lateral extension at one 35 side of the blank having a rectilinear side edge extending parallel to said two mutually spaced rectilinear fold lines, the extreme sidewise edge portions of the side of the blank opposing said rectilinear side edge being substantially parallel to said rectilinear side edge, thereby affording flat foldability of the blank upon itself, with opposing portions of the blank overlying one another. 40
35. 15. A container formed of a blank of foldable material, the walls thereof when the container is set up, comprising alternate concave and convex panels, irregular score lines defining the marginal edges of said concave and convex panels and serving the connection between the panels, said irregular score lines being arranged in pairs in opposed relation whereby setting up of the box produces the aforementioned concave and convex panels and produces tension therein, said blank being further provided with two mutually spaced rectilinear fold lines extending non-parallelly to said irregular score lines, said blank further comprising a lateral extension at one 45 side of the blank having a rectilinear side edge extending parallel to said two mutually spaced rectilinear fold lines, the extreme sidewise edge portions of the side of the blank opposing said rectilinear side edge being substantially parallel to said rectilinear side edge, thereby affording flat foldability of the blank upon itself, with opposing portions of the blank overlying one another. 45

MARSHALL I. WILLIAMSON.
